UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 8, 1922. Serial No. 541,911.

To all whom it may concern:

Be it known that I, RAYMOND B. GILCHRIST, a citizen of the United States, and a resident of Newark, in the county of Essex and State of New Jersey, have invented certain new and useful Improvements in Drink Mixers, of which the following is a full, clear, and exact description.

The invention relates to drink mixers. In machines for this purpose, the liquid constituents of the drink to be mixed are usually poured into a receptacle which is generally designated a "shaker," from many different containers disposed away from the mixer. The receptacle with these constituents therein is brought to the mixer and placed in operative relation thereto and is removed from the machine after each mixing operation, to discharge its contents. This is rendered necessary, because so many different ingredients and flavors are used in making drinks that they are, in nearly all cases, mixed individually. It is usually necessary to run the agitator for a considerable period to properly blend or mix the constituents and, therefore, it is desirable that provision be made for retaining the receptacle and agitator in operative relation to permit the dispenser to perform other duties during the mixing operation. In drink-mixing, it thus becomes necessary to frequently place the receptacle containing the constituents into cooperative relation to the agitator and to withdraw it from the machine to discharge its contents and cleanse the receptacle between mixing operations.

A desideratum in this art is to expedite and simplify the operations necessary to bring the receptacle and agitator into cooperative relation, to maintain them in such relation, in starting and stopping of the motor and the removal of the receptacle. Heretofore, in machines whereof I am aware (excepting those exhibited in other concurrently pending applications), it has been necessary in their use to manually manipulate the receptacle into operative position and withdraw it therefrom and to additionally perform some separate step or operation, such as lowering the motor and agitator together, or shifting the agitator and its shaft into the receptacle and relatively to the motor, or raising and locking a receptacle-support to establish and maintain coop-

erative relation of the receptacle and agitator or to control the operation of the machine. Another desideratum in this art is to simplify the machine by dispensing with movable connections in and for the driving mechanism for the agitator.

One object of the present invention is to provide an improved drink mixer in which these additional operations or steps are dispensed with and in which manual shift of the receptacle is utilized to completely control the operation of the machine and to secure it and the agitator in cooperative relation. By dispensing with the necessity of these additional steps or operations, the time of the dispenser in performing them is saved and the service is improved.

Another object of the invention is to provide a machine of this type in which movable connections in and for the driving mechanism for the agitator are dispensed with.

Another object of the invention is to provide a machine which is simple in construction, which may be easily and readily operated and which is efficient in operation.

Other objects of the invention will more fully appear from the following description.

The invention consists in the several novel features hereinafter set forth and more particularly defined by claims at the conclusion hereof.

In the drawings: Fig. 1 is a vertical section of a machine embodying the invention parts being shown in elevation. Fig. 2 is a section on line 2-2 of Fig. 1. Fig. 3 is a detail of the hook-connection between the receptacle and the guide.

The invention is exemplified in a machine comprising an electric motor 10 of usual construction, to the rotor of which is secured a pendent shaft 11 with an agitator 12 fixed to its lower end; a hollow supporting standard comprising a lower portion 13 fixed to a bottom-member 14 which is secured to a base 15 by a screw 16, and an upper member 17 suitably secured in the member 13; and a bracket 18 suitably secured to the upper end of member 17, to which the motor 10 is suitably secured, as at 19. The electrical connections for supplying energy to the motor 10 comprise a conductor-cord 20 leading through a handle 21 and comprising con-

ductors 22 and 23 connected to the motor, and normally disconnected switch-members 24 and 25 being included in the conductor 23 to control the operation of the motor. 5 The casing of the motor 10 is fixedly secured to the support at 19 and the agitator 12 is maintained in substantially relatively fixed vertical relation to the motor.

A receptacle 26 having an open top, a 10 closed bottom 27 and an upper downwardly extending flange 29, is adapted to contain the constituents of the drink to be mixed and to be placed into cooperative relation to the agitator from beneath the latter, which 15 is supported sufficiently above the base 15 to permit the insertion and withdrawal of the receptacle.

The invention contemplates placement of the receptacle into and out of operative relation to the agitator, locking and unlocking the receptacle and control of the motor by manipulation of the receptacle itself, so that shift of the motor or the agitator are not necessary to bring the agitator into working 25 position in the receptacle. For this purpose, a stationary vertically extending receptacle-guide is provided for the back of the receptacle and comprises a lower inclined or upwardly and backwardly sloping 30 member or portion 30 and a vertical upper portion 31. The guide has its front face curved or arcuate in substantial conformity with the outer periphery of the receptacle so that when the latter is pressed backward- 35 ly against the guide, the receptacle will be guided against lateral movement and into its operative position without danger of striking the agitator 12.

The receptacle is adapted to be removably 40 secured in its operative position by the flange 29 which constitutes an annular hook adapted to extend around the arcuate upper end of the stationary guide member 31. A guard member 33, which is secured to stand- 45 ard member 17 by screws 33', extends over the upper rim of the receptacle and downwardly into it so as to form a stop for limiting the upward movement of the receptacle and also for limiting the forward movement 50 of the upper portion of the receptacle, to prevent it from striking the agitator. By suspending the rear portion of the receptacle from the upper end of the guide, the weight of the front portion of the receptacle 55 and the material therein will tend to hold the receptacle against guide member 31. The stationary receptacle guide is secured to the standard by lugs 32.

For the purpose of automatically controlling 60 the operation of the motor by manipulation of the receptacle, a switch-lever 34 has its lower end 35 formed to pivotally fit in the lower end of the standard-member 13 and on the plate 14, is extended through a 65 slot 36 in front of the supporting-standard and

through a slot 37 formed in guide-member 31 and is provided with a cam-portion 38 which is adapted to be struck by the receptacle 26 while it is being raised into operative position and to be held in shifted position as 70 long as the receptacle is secured in its operative position. A stop-shoulder 34' is provided on lever 34 to limit the forward movement of the lever under the influence of spring 43, so it will be normally projected 75 into the path of the receptacle the correct distance to operate the motor-switch. Lever 34 is also formed with a cam 39 in the hollow standard, to shift and control a plunger 40 which is slidably held in the hollow- 80 standard and carries a switch-pin 41 at its upper end which is adapted to bridge the gap between the normally separated switch-members 24 and 25 and close the circuit for the 85 operation of motor 10. Switch-members 24 and 25 are secured to a block 42 of insulating material. Plunger 40 may be formed of insulating material, such as wood, and is normally pressed downwardly by a spring 43 interposed between a shoulder on the 90 plug and a plate of insulating material 44 suitably held in the upper end of the standard-member 17. A wear-plate 45 is secured to the lower end of plunger 40.

The operation of the machine will be as follows: Assuming the parts to be in normal position shown in Fig. 1, the operator will place receptacle 26, containing the constituents of the drink to be mixed, against inclined guide-member 30 and under the agitator 12, as shown by dotted lines in Fig. 1, press it rearwardly with sufficient force to cause the guide to laterally control its vertical movement, and then lift it. In this manipulation, the receptacle will slide on the front-face of the receptacle-guide. After the receptacle leaves the inclined guide-member 30, it will bear against the vertical guide-member 31 and be raised until its upper margin passes into the holder-member 33. When the receptacle strikes member 33, the hook flange 29 will slip backwardly above the upper end of guide member 30. The operator will then release the receptacle or exert a downward pressure on it to cause the hook-flange and the guide to positively interlock and secure the receptacle in its operative position. In its upward movement, the receptacle will engage the cam 38 and rock lever 34 about its lower end so that cam 39 will raise plunger 40, cause the pin 41 to bridge switch-members 24, 25 and close the circuit for the operation of the motor 10 and cause it to drive the agitator. This occurs, preferably before the receptacle reaches its operative position. The hook connection between the receptacle and the guide positively holds the receptacle, so that it will not be displaced by the forward pressure of switch-lever 34, which is under the influence 115 120 125 130

of spring 43, which tends to hold the switch-lever normally in the path of the receptacle. When the motor has run for the desired period and the mixing operation has been completed, the operator will lift receptacle 26 sufficiently to release hook-flange 29 and then tilt the upper portion of the receptacle forwardly into contact with the downwardly extending portion of the guard 33. Then, the operator will lower the receptacle and press it backwardly, so that it will be held in the stationary guideway until it has been lowered to clear the agitator when it may be withdrawn forwardly. During the lowering of the receptacle, the switch-lever 34 will pass into its normal position to release plunger 40 and cause it to break the circuit and stop the motor. This occurs preferably after the vessel has been lowered, to bring the liquid therein below the agitator, so the latter will run for a period to discharge the adherent liquid by centrifugal force before the agitator leaves the upper end of the receptacle.

The invention exemplifies a machine of the character described, in which the receptacle is manually placed and locked in its operative position; in which such placement controls the motor; which is simple in construction and avoids the necessity of a shiftable agitator.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a drink mixer, the combination of a support, an electric motor mounted on the support, an agitator driven by the motor and supported from above with sufficient clearance to permit a receptacle with an open top to be placed into its operative position around the agitator, and means to automatically retain the receptacle in its cooperative relation with the agitator upon manual manipulation of the receptacle itself into such relation, consisting of a hook connection for the upper portion of the receptacle and whereby it will be supported vertically and held laterally.

2. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of a hook connection for the upper portion of the recep-

tacle and whereby it will be supported vertically and held laterally, and means for automatically controlling the operation of the motor by shift of the receptacle to and from its hooked position.

3. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of a hook on the upper portion of the receptacle and suspension means on the support for engagement with the hook and whereby the receptacle will be supported vertically and held laterally.

4. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of a hook on the upper portion of the receptacle and suspension means, whereby it will be supported vertically and held laterally, means for automatically controlling the operation of the motor by shift of the receptacle to and from its hooked position.

5. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of an annular hook on the upper portion of the receptacle, and means to engage with a portion only of the hook and whereby the receptacle will be supported vertically and held laterally.

6. In a drink-mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of an annular hook on the upper portion of the receptacle and

means to engage with a portion only of the hook and whereby the receptacle will be supported vertically and held laterally, and means for automatically controlling the operation of the motor by shift of the receptacle to and from its hooked position.

7. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of a down-turned flange on the upper rim and spaced from the outer face of the receptacle to form an annular groove and means to enter said groove to support the receptacle.

8. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of a down-turned flange on the upper rim and spaced from the outer face of the receptacle to form an annular groove, means to enter said groove to support the receptacle, and means for automatically controlling the operation of the motor by shift of the receptacle to and from its hooked position.

40 9. In a drink mixer, the combination of a support, an electric motor mounted on the support, an agitator driven by the motor and supported from above with sufficient clearance to permit a receptacle with an open top to be placed into its operative position around the agitator, means to automatically retain the receptacle in its cooperative relation with the agitator upon manual manipulation of the receptacle itself into such relation, consisting of a hook-connection for the upper portion of the receptacle, whereby it will be secured vertically and laterally, and means for automatically controlling the operation of the motor by shift of the receptacle to and from its hooked position, said hook-connection being adapted to hold the receptacle to retain the controlling means so as to keep the motor running while the receptacle is hooked in position.

10. In a machine of the character described, the combination of a support, a motor, an agitator driven by the motor and supported from above with sufficient clearance to permit a receptacle with an open

top to be placed into operative position around the agitator, means to slidably guide the receptacle into and out of operative position and a hook-connection for securing the receptacle in operative position.

11. In a machine of the character described, the combination of a support, a motor, an agitator driven by the motor and supported from above with sufficient clearance to permit a receptacle with an open top to be placed into operative position around the agitator, means to slidably guide the receptacle into and out of operative position, and a hook-connection between the receptacle and the guide, for securing the receptacle in operative position.

12. In a machine of the character described, the combination of a support, a motor, an agitator driven by the motor and supported from above with sufficient clearance to permit a receptacle with an open top to be placed into operative position around the agitator, stationary means to slidably guide the receptacle into and out of operative position, and a hook-connection between the receptacle and the guide, for securing the receptacle in operative position.

13. In a machine of the character described, the combination of a support, a motor, an agitator driven by the motor and supported from above with sufficient clearance to permit a receptacle with an open top to be placed into operative position around the agitator, a hook connection for securing the receptacle in operative position, and means for limiting the movement of the receptacle relatively to the support.

14. In a machine of the character described, the combination of a support, a motor, an agitator driven by the motor and supported from above with sufficient clearance to permit a receptacle with an open top to be placed into operative position around the agitator, a hook for securing the receptacle in operative position, and a stop extending into the receptacle to limit its forward movement.

15. In a machine of the character described, the combination of a support, a motor, an agitator driven by the motor and supported from above with sufficient clearance to permit a receptacle with an open top to be placed into operative position around the agitator, a hook for securing the receptacle in operative position, and a stop extending over the rim of and into the receptacle for limiting the upward movement of the receptacle.

16. In a machine of the character described, the combination of a support, a motor, an agitator driven by the motor and supported from above with sufficient clearance to permit a receptacle with an open top to be placed into operative position around the agitator, a hook between the receptacle and

the support, and means for controlling the operation of the motor shifted by the receptacle.

17. In a machine of the character described, the combination of a support, a motor, an agitator driven by the motor and supported from above with sufficient clearance to permit a receptacle with an open top to be placed into operative position

around the agitator, a hook on the upper end of the receptacle to engage the support and hook the receptacle in operative position, a stationary stop for limiting the movement of the receptacle relatively to the support.

Signed at Newark, N. J., this 11th day of February, 1922.

RAYMOND B. GILCHRIST.
